UNITED STATES PATENT OFFICE.

HUGO S. HASSELQUIST, OF OAK PARK, ILLINOIS, ASSIGNOR TO COLLINS ROTARY SAFETY RAZOR COMPANY, OF CHICAGO, ILLINOIS, A CORPORATION OF SOUTH DAKOTA.

CENTRIFUGAL GOVERNOR.

1,407,413.

Specification of Letters Patent. Patented Feb. 21, 1922.

Application filed August 28, 1919. Serial No. 320,354.

To all whom it may concern:

Be it known that I, HUGO S. HASSELQUIST, a citizen of the United States, residing at Oak Park, in the county of Cook and State 5 of Illinois, have invented certain new and useful Improvements in Centrifugal Governors, of which the following is a specification.

My invention concerns governors of the 10 centrifugal fly-ball type, its leading object being the production of a governor or regulator of this general form and style which occupies but small space, which is composed of but few parts of simple structure, which 15 is economical to produce, which is compact in construction and hence not subject to injury, and which will operate with efficiency and reliability. While the invention is susceptible of embodiments to advantage in 20 structures of relatively large size, it is especially adapted for incorporation in devices of small dimensions where the space which it occupies is a more or less important factor.

25 To the accomplishment of these desirable ends, the governor or regulator is constructed to fit closely around the shaft the speed of which it controls, and accordingly its structural elements are shaped and formed and 30 brought into proper co-operative relation with this purpose in view.

In order that those skilled in this art may 35 have a full and complete understanding of the invention and its various structural and functional advantages, I have illustrated in the accompanying drawing, forming a part of this specification, and throughout the various views of which like reference characters refer to the same parts, a preferred 40 and desirable embodiment of the invention, it being understood that the governor may be made of a size much smaller than the illustration and yet operate satisfactorily and effectively.

45 In this drawing:

Figure 1 is a plan view of the structure;

Figure 2 is an elevation or front view of the same;

Figure 3 is a vertical section through the 50 center of the shaft; and

Figure 4 illustrates the shape of the flat plate from which the main governor body is formed.

Referring to the drawing, it will be seen

that the appliance includes a base-plate 10 with upstanding end arms or supports 11 and 12 affording bearings 13 and 14 for a shaft 15 having for a portion of its length a spiral gear 16 driven or rotated by a larger spiral or helical gear 17 on a shaft 18 at right-angles to the shaft 15 and revolvable in bearings in the base-plate 10 and in a superposed plate 19 supported on the base-plate by a plurality of posts 20 of which only one is shown in the drawing. Gear 17 is driven by other suitable gearing not shown.

At one end the shaft 15 is provided with a cylindrical collar 21 fixedly secured thereto by a set-screw 22, one half of the collar being cut away at one end, leaving an inwardly-projecting semi-circular part or extension 23. Such extension and a portion of the main body of the collar are internally provided with a cylindrical recess 24 receiving a portion of a coil-spring 25 surrounding or encircling the shaft.

Also fitted on and slidable on the shaft is a cylindrical sleeve 26 having a brake-flange 27 at one end, the sleeve for a portion of its length at one end being cut away leaving a semi-cylindrical projection 28 occupying the space provided by the cutting away of the collar 21, the extension 23 of the latter occupying the space provided by the omitted portion of the sleeve. In other words, the collar and sleeve are interfitted, the extensions of the two unitedly or conjointly forming an intermediate cylindrical part. The sleeve is internally recessed at 29 similar to the cavity in the collar for the accommodation of the remainder of the coil-spring, which tends to slide the sleeve along the shaft away from the collar, all as will be readily understood.

The appliance is fitted with a stationary brake-block 30 on an adjustable arm 31 adapted to co-act with the brake-disc 27 to govern or regulate the speed of rotation of the shaft.

The governor proper comprises a member bent up or shaped to form from a flat plate of the shape illustrated in Figure 4. It comprises a central strip or strap portion 40 bent transversely into circular form around the two matching extensions of the collar and sleeve, that is to say, around the interfitted parts of such two elements. This

portion of the governor has a screw 41 in a threaded hole 42 thereof, the inner rounded end of the screw fitting in a cavity 43 of approximately the same size in the outer face of the collar extension 23, such part acting as a fulcrum for the governor. Another part of the strap portion 40 is provided with a threaded hole 44 therethrough for a screw 45, the inner rounded end of which fits in a hole 46 in the outer face of the sleeve extension 48. It will be understood, therefore, that as the governor rocks slightly transversely to the shaft, around the fixed fulcrum 41 by reason of the connection 45, 46, it will slide the sleeve along the shaft in opposition to the action of spring 25.

Opposite the hole 42 the governor has a narrow neck portion 47 curved transversely around a part of the collar 21 and at its end such neck has an enlargement or weight portion bent transversely in semi-circular form half way around the main body of the collar.

In similar manner opposite the hole 44 the bar or stop 40 has a neck 49 bent transversely around a part of the sleeve and such neck carries a weight portion 50 bent into semi-circular form around one-half of the sleeve.

As is clearly shown, this governor fits over the collar and sleeve somewhat loosely so that it is capable of moving or shifting slightly laterally of these parts.

The operation of the device occurs practically as follows:

When the speed of rotation of the shaft increases, the governor weights 48 and 50 move outwardly under the influence of centrifugal force, the governor as a whole turning about the fulcrum or pivot member 41. This movement causes the screw or pin 45 to travel to the left as the parts are viewed in Figure 3, shifting the sleeve 26 with it in the same direction and bringing the brake-disc 27 into contact with the stationary brake-member 30 with a pressure corresponding or proportional to the speed increase. This, of course, puts a braking action on the shaft, which slows down the speed of revolution to the proper amount. If the speed of rotation of the shaft decreases below the normal the brake-disc 27 is moved away from the stationary brake element 30 by reason of the inward movement of the weights 48 and 50, it being obvious that to move the brake-disc to the left the centrifugal force acting on the weights must be sufficient to overcome the expanding tendency of the coil-spring 25. By thus governing and regulating the braking action on the sleeve and shaft the governor, as a whole, controls the speed of rotation and maintains it within well defined limits of change.

Although in this application one preferred

desirable embodiment of the invention has been presented in detail, it will be understood by those skilled in the art that the invention is susceptible of a variety of embodiments differing materially in mechanical respects, but all possessing the benefits and advantages accruing from the employment of the invention. The invention, therefore, is not restricted to the precise embodiment illustrated and described and many features in the construction may be varied without departure from the substance of the invention and without sacrificing any of its substantial benefits and advantages.

I claim:

1. In a centrifugal governor of the character described, the combination of a rotary shaft, means to revolve the shaft, a chambered collar surrounding and secured to said shaft having a recess on one side, a chambered sleeve slidably mounted on said shaft having a part extended into the recess of said collar, a coil-expansion-spring surrounding said shaft between and accommodated in the chambers of said collar and sleeve tending to slide the latter along the shaft, a brake-disc carried by said sleeve, a relatively-stationary brake-member adjacent to said disc, and a governor having a central portion bent around the interfitted parts of the collar and sleeve, fulcrumed on said collar, and having an operative connection with said sleeve, said governor having neck portions extended in opposite directions from said central part and on opposite sides of the collar and sleeve, and weight portions at the ends of said necks bent partially around the collar and sleeve in opposite directions, substantially as described.

2. In a centrifugal governor of the character described, the combination of a rotary shaft, means to rotate said shaft, a sleeve slidably lengthwise on said shaft, a brake-disc on said sleeve, a relatively-stationary brake-shoe adjacent to said disc, a spring acting on said sleeve to slide it in one direction on the shaft, a centrifugal governor fulcrumed at its central part on said shaft and also having at its central portion an operative connection with said sleeve, the end portions of the governor being bent in opposite directions transversely to partially encircle the shaft and sleeve, substantially as described.

3. In a centrifugal governor of the character described, the combination of a rotary shaft, means to rotate said shaft, a sleeve slidably lengthwise on said shaft, a brake-disc on said sleeve, a relatively-stationary brake-shoe adjacent to said disc, a spring acting on said sleeve to slide it in one direction on the shaft, and a centrifugal governor fulcrumed substantially midway of its length on said shaft and having an operative connection substantially midway of its

length with said sleeve, said governor being bent transversely to partially encircle said shaft, substantially as described.

4. In a centrifugal governor of the character described, the combination of a rotary shaft, means to revolve said shaft, a chambered collar surrounding and secured to said shaft and having a recess on one side, a chambered sleeve slidably mounted on said shaft having a part extended into the recess of said collar, a coil-expansion-spring surrounding said shaft between and accom-

modated in the chambers of said collar and sleeve tending to slide the latter along the shaft, a brake-disc carried by said sleeve, a relatively-stationary brake-member adjacent to said disc, and a governor fulcrumed on said collar and having an operative connection with said sleeve, said governor having at least a portion thereof bent transversely to partially surround the shaft, substantially as described.

HUGO S. HASSELQUIST.
